UNITED STATES PATENT OFFICE.

JULIUS PEGEL, OF PHILADELPHIA, PENNSYLVANIA.

DESIGN FOR A RUG.

SPECIFICATION forming part of Design No. 19,492, dated December 17, 1889.

Application filed November 23, 1889. Serial No. 331,375. Term of patent 3½ years.

To all whom it may concern:

Be it known that I, JULIUS PEGEL, a citizen of the United States, and a resident of Philadelphia, Pennsylvania, have invented a Design for Rugs, of which the following is a description, reference being had to the accompanying photographic illustration, making part hereof.

A is the middle panel, oblong and arched, with scallops B at one end, the panel being narrowed at part C.

D is a narrow outer border scalloped on its inner edge.

E are leaves upon the outer edge of the arch or curved end of the panel.

F are fanciful figures ornamented with rosettes or flowers and located between the panel and the border; G, a middle double

spray of leaves and flowers between one end of the panel and the border, near the latter; J, a fancy figure in the lower part of the panel, with upwardly-projecting sprays K of flowers and leaves; H, a large fanciful figure below the panel A, containing scroll-work and having the general form of a fan with an upper scalloped edge.

I are fanciful corner pieces.

What I claim as new is—

A design for rugs, as shown.

In witness that the above is my invention I have hereunto set my hand.

JULIUS PEGEL.
